BEVERAGE VENDING MACHINE

Hubert M. Giepen, Chicago, Ill., assignor, by mesne assignments, to Giepen Associates, River Grove, Ill., a corporation of Illinois

Filed Jan. 13, 1960, Ser. No. 59,039

Term of patent 3½ years

(Cl. D52—3)

FIG. 1.

Fig. 2 is a front elevation of the machine shown in Fig. 1; and

Fig. 3 is a right side elevation of the machine shown in Fig. 1.

The back and left side of the machine shown in the preceding figures are plain and unornamented.

I claim:

The ornamental design for a beverage vending machine, substantially as shown and described.
